UNITED STATES PATENT OFFICE

1,956,663

STOVE

Frank E. Wolcott, West Hartford, Conn., assignor to The Silex Company, a corporation of Connecticut

Application November 25, 1930, Serial No. 498,055

32 Claims. (CL. 126—40)

My invention relates to stoves.

It has among its objects to provide an improved stove and more particularly an improved stove of the type used in restaurants or the like. A further object of my invention is to provide an improved gas stove having an improved stand or casing housing the burners and the connections thereto, improved utensil supporting means above the burners, and improved connections for the burners. These and other objects and advantages of my improved construction will, however, hereinafter more fully appear.

In the accompanying drawings I have shown for purposes of illustration one embodiment 15 which my invention may assume in practice.

In these drawings,—

Figure 1 is a plan view of my improved stove, certain of the utensil supporting grid members and burners being removed to facilitate illustration;

Figure 2 is a front elevation of the stove, but, to facilitate illustration, with one corner thereof broken away and the other corner post shown in section on line 2—2 of Figure 1;

Figure 3 is a sectional view on line 3—3 of Figure 1;

Figure 4 is a detail plan view of one of the corners with the cap removed from the corner housing;

Figure 5 is a bottom plan view of one of the corners;

Figure 6 is a section on line 6—6 of Figure 1, showing one of the grid supporting members in elevation;

Figure 7 is an inside perspective view of the base of one of the casing corners;

Figure 8 is a perspective view of one of the corner housing members;

Figure 9 is a top plan view of the housing member shown in Figure 8, and

Figure 10 is a detail plan view of one of the removable grid members.

In this illustrative construction, hereinafter more specifically described, I have shown my improved stove as comprising a casing, generally indicated at 1, and of substantial rectangular form, having corner housings 2 which also act to form supporting legs for the casing, while a plurality of burners 3 are provided inside the casing and beneath a supporting grid structure, generally indicated at 5, and gas is supplied to these burners through supply connections 6 disposed in the casing and controlled by control members 7 on the front of the casing.

Referring more particularly to the casing, it

will be observed that the same comprises a front elongated sheet metal plate 8, a corresponding rear plate 9, and shorter end plates 10 and 11. It will also be noted that the plates 8 and 9 carry on and inside their upper edges corresponding grid holding strip members 12 and 13, while corresponding members 14 and 15, which have no grid holding function, are carried on the upper edges of the plates 10 and 11. Attention is also directed to the fact that the plates 8 and 9 are provided with inwardly extending flanges 16 on their lower edges, while the plates 10 and 11 are provided with corresponding flanges 17 on their lower edges. As shown, both sets of flanges are also spaced or cut away at the corners to provide an open space indicated at 18, while the flanges act as supports for a bottom plate or member 19 having diagonally cut off corners likewise exposing the space 18, and are connected to this member 19 by suitable means, as for example, screw connections 20. Here it will also be noted that at each corner the adjacent vertical plates overlap, inturned lateral extensions 21, for example, being provided on the end plates 10 and 11 and connected to ends of the plates 8 and 9 by suitable connecting means such as rivets 22. Thus it will be evident that the casing 1 is of a rugged, yet simple construction stiffened by the members 12, 13, 14 and 15 and by the bottom member 19, while being rigidly connected at its corners.

Upon each of the corners of this casing, housing members are provided substantially corresponding to those described and claimed in my co-pending application, Serial No. 498,058, filed November 25, 1930. More particularly considering the corner construction, it will be noted that I have shown the housing members 2 as having right angled slots 23 and 24 in their upper ends of sufficient size to receive and support the ends of the members 12, 13, 14, 15 when the members 2 are inserted from the bottom. Herein also it will be noted that below these slots are extended elongated more narrow slots 25 which are adapted to receive the plate members adjacent the corner, as for example, the plate members 9 and 10. Referring more particularly to the corner shown in Figures 4, 5, 7 and 8, it will be noted that the member 2 is thus adapted to be inserted from the bottom so that these side and end plates 9 and 10 will be received in the slots 25 substantially as described in my previously mentioned application, while the ends of the members 13 and 14 will be received and supported in the enlarged slots 23 and 24 in the member 2. Also it will be

observed that in this construction the plate member 10 is provided with a vertical notch 26 in its lower end adjacent one edge of the portion 21, while the plate 9 is provided with a pair of corresponding notches 27 of which the outer notch is spaced the same distance from the corner as the notch 26. Thus it will be evident that the slotted portions 25 on the leg member 2 will be adapted to fit in these notches 26, 27 and that the parts are securely connected at the bottom as well as at the top, while the member 2 encloses both the inside and outside of the corner. Here it will also be noted that, as in my previously described construction, a cap 28 is fitted on the top 15 of each leg 2 and connected by a rod 29 extending down inside the corner of the casing, as shown in Figure 4, and connected at its lower end to a foot member 30 by means of a nut and screw connection 31, all in the general manner of my previous application.

Referring more particularly to the grid means, it will be observed that the members 12 and 13 supporting the same are of substantially identical construction so that a description of one will suffice for both. More particularly, it will be noted that each of these members 12, 13 is attached by suitable means 12', herein rear screws and front rivets, to its outside plate, and that it is disposed flush with the top edge of the latter 30 and provided with a series of apertures and notches adapted to support the grid means 5. Taking the member 13, for example, and referring to Figure 6 which shows slightly more than one half of this member in elevation, it will be observed that the same is provided at its right hand end and just inside the corner with a pair of laterally spaced apertures 32, and that adjacent them to the left four laterally spaced open notches 33 are provided in its upper surface. 35 Next to these notches to the left is another pair of apertures 32 and next to these at the left, another set of four open notches 33. Beyond the latter notches and midway between the ends of the member 13 is another pair of apertures. 40 Of these, the more remote corresponds to an aperture 32 in being unthreaded, while the other, nearer to the notches and marked 34, is threaded. The rest of the member 13 being of the same construction heretofore described needs no further 45 description, nor does the member 12 save to say that its aperture corresponding to the aperture 34 is oppositely threaded.

Thus with the two members 12 and 13 so constructed, it is made possible to seat rods 35 in each of the registering unthreaded apertures 32. As shown, the oppositely threaded apertures 34 are also connected by a single tie rod 36 oppositely threaded on its opposite ends and preferably provided with means to facilitate turning the 50 same and herein in the form of an aperture 36' adapted to receive a suitable pin or tool. It will also be noted that removable rod or grid members are disposed in the notches 33 which in the arrangement described are in the areas above the 55 burners 3. Here it will also be observed that these removable grid members comprise oppositely disposed units. More particularly, each comprises a straight rod or grid member 37 having pivotally connected thereto midway between its ends, as 60 by a rivet 38, a co-operating member 39 disposed parallel thereto at its ends and provided intermediate its ends with an arcuate portion 40 connected to the rivet 38, while the two arcuate portions 40 serve to present a substantially round 65 grid substantially spaced above the burner 3.

More particularly considering the gas supply and control connections, it will be noted (Figure 1) that the supply connection or piping 6 is extended through the right hand end of the rear plate 9 and suitably rigidly connected thereto as 80 at 41 close to the bottom of the same. As shown, it is also extended forwardly along the side 11 and then longitudinally of the casing in the form of an extension 42 close to and parallel to the plate 8 and attached to the bottom 19 of the casing by strips 43. Herein, this extension carries usual burner connections 44 spaced along its length, each of which in turn carries usual longitudinally separable burners 3 and is controllable by a usual controlling member 7. Herein it will 85 also be observed that burners 3 are in the form of single elongated members having an upwardly directed pierced outlet at one end. It will also be noted that each burner is provided with a threaded aperture 45 in its under surface substantially beneath its delivery end and that a supporting rod 46 is threaded in this aperture and also provided with a threaded lower end threaded in a corresponding aperture 47 in a nut member 48 carried in the under side of the 100 bottom member 19, a corresponding aperture of course being provided in the latter. As shown, the member 46 is also provided with suitable turning means, herein in the form of a transverse pin 49, so that it may be readily turned, while the nut 48 105 is suitably attached to the plate 19 as by rivets 50. Attention here is also directed to the fact that the bottom plate 19 is provided with suitable air apertures 51, herein preferably disposed in spaced relation in a plurality of lines extending longitudinally of the same on opposite sides of the 110 line of burners 3.

As a result of my improved construction, it will be observed that a very rugged, yet inexpensive, casing is produced which is of the open grid top 115 type, and particularly adapted to use in connection with gas or other liquid fuel type burners. By reason of the improved grid supporting members inside the upper edges of the outer front and rear plates, and the connection to or support 120 of the several grid members on these supporting members, it will be noted that not only is a strong, yet simple, construction made possible, but that overheating and consequent discoloration of the outer plates is minimized, at the same 125 time that the grids are disposable entirely within the outer plates in such manner as to improve the appearance of the structure and also to eliminate any possibility of the end of any grid being engaged or accidentally thrown out of position 130 relative to the casing during use. It will also be noted that it is made possible to apply my improved corner housing means to this casing in such manner as to increase the strength of the same while producing a very attractive appearance and also to enable a series of casings to be connected end to end by improved connecting members as described in my above mentioned application. Attention is also directed to the fact 135 that the improved grid means are such as, while providing a grid surface of large area, to enable the grid members 35 to be held in position by the tie rod 36 regardless of changes in temperature, and to enable access to be had to the burners and their connections whenever desired through the 140 removable grid units comprising the pivotally connected members 37, 39. It will also be observed that by simply removing one or both of these removable units and adjusting the member 46 supporting the burner, it is possible to adjust the 145 150

burner 3, as desired, while the member 46 may, whenever desired, be so rotated as to permit removal of the burner. These and other advantages of my improved construction will, however, be 5 clearly apparent to those skilled in the art.

While I have in this application specifically described one embodiment which my invention may assume in practice, it will be understood that this form of the same is shown for illustrative purpose 10 and that the structure may be modified and embodied in various other forms without departing from its spirit or the scope of the appended claims.

What I claim as new and desire to secure by Letters Patent is:—

1. A stove casing comprising generally vertically disposed front, back and end plates, means rigidly connecting adjacent plates at their meeting edges, and separable corner housing and covering means enclosing said connecting means and the meeting edges of said plates and clamping said casing therebetween.

2. A stove casing comprising generally vertically disposed front, back and end plates rigidly connected and having an open top, and corner housing and covering means enclosing the meeting edges of said plates, and a tie rod carried by said housing and covering means clamping said casing therebetween.

3. A stove casing comprising generally vertically disposed front, back and end plates rigidly connected at their meeting edges and having an open top and grid supports on confronting plates, and corner housing and covering means enclosing the meeting edges of said plates and the ends of said grid supports and clamped to said casing.

4. A stove casing comprising generally vertically disposed front, back and end plates rigidly connected at their meeting edges and having members on their upper edges terminating short of the corners, grid means carried by certain of said members, and separable corner housing and covering means enclosing the meeting edges of said plates and clamping said casing therebetween.

5. A stove casing comprising front, back and end plates rigidly connected at their corners and having member on their upper edges, grid means carried by certain of said members, and corner housing means housing the corners and the adjacent extremities of said members.

6. A stove casing comprising outer front, back and end plates rigidly connected at their corners and having members inside their upper edges, grid means carried by certain of said members, and corner housing members insertable from the bottom of each corner and having slots receiving said outer plates and slots in their upper ends receiving the extremities of said members.

7. A stove casing comprising outer front, back and end plates rigidly connected at their corners and having members inside their upper edges, grid means carried by certain of said members, corner housing members insertable from the bottom of each corner and having slots receiving said outer plates and slots in their upper ends receiving said members, and cap and foot members carried by said housing members having connecting means disposed within said connected corners.

8. A stove comprising a casing having an open top, heating means in said casing, grid supporting members along opposite sides of the latter, grids having their ends supported on said members and bodily removed at will, and a tie rod oppositely threaded into opposite grid supporting

members and adjustable at will to adjust the latter with respect to each other and said ends.

9. A stove comprising a casing having an open top, heating means in said casing, grid supporting members carried by confronting walls of said casing, grid members having their opposite ends supported by said supporting members and disposed thereon below the open top of said casing and bodily removable at will from said supporting members, and means for effecting relative movement of said confronting walls toward each other and into gripping engagement with the ends of said grid members.

10. A stove comprising a casing having an open top, heating means in said casing, grid supporting members carried by confronting walls of said casing above said heating means having spaced grid receiving recesses, a plurality of independently supported grid members having their opposite ends loosely received in the recesses of said supporting members and between the confronting walls of said casing, and a member having provision for holding all of said grid members releasably in the aforesaid position relative to said supporting members and casing walls including right and left screw-threaded connections at its opposite ends with said grid supporting members.

11. In a stove, a casing having heating means therein and opposing grid supporting members therein provided with registering apertures and notches, a tie rod reversely threaded into certain registering apertures and extending between said members, grid members in the remaining apertures, and removable grid members in said notches.

12. In a stove, a casing having heating means therein and opposing grid supporting members therein provided with registering apertures and notches, a tie rod extending between said members and being reversely threaded into certain registering apertures intermediate the ends of said members, grid members in the remaining apertures, and removable grid members in said notches.

13. A stove having an open top casing including opposed side walls, heating means therein, grid supporting members located within and on opposite sides of said casing having notches therein disposed below the open casing top, a plurality of grid units separately removably supported on said members wholly within the confines of said casing side walls having straight end portions supported loosely in said notches and arcuate intermediate portions, and means for supporting said arcuate portions in the plane of the straight portions of the several grid units.

14. A stove having a casing, heating means therein, grid supporting members on opposite sides of said casing having notches in their upper edges, and a plurality of oppositely disposed grid units supported in said notches, each of said units comprising a straight rod and a co-operating rod pivotally connected thereto intermediate its ends.

15. A stove having a casing having a bottom, burner supply connections therein having a burner separable from the latter and projecting therefrom over the casing bottom, and adjustable means carried by said casing removably secured to and supporting said burner, said means comprising a single member extending from said casing bottom upwardly to the underside of said burner substantially in line with the axis of the latter.

16. A stove having a casing having a bottom,

- burner supply connections therein having a burner separable from the latter and projecting therefrom over the casing bottom, and adjustable means carried by the bottom of said casing removably secured to and supporting said burner, said means comprising a single threaded member threaded in the bottom of said casing and into the under side of said burner at substantially the axis thereof.
- 10 17. A stove having a casing, burner supply connections therein having a burner separable from the latter, adjustable means carried by said casing removably secured to and supporting said burner, said means comprising a single threaded member threaded in the bottom of said casing and into the under side of said burner at substantially the axis thereof, said threaded member carrying turning means intermediate its ends and the bottom of said casing carrying a nut receiving the lower end of said threaded member.
- 15 18. A stove having a casing including a bottom wall, burner supply connections therein, a burner including a lateral extension having a telescoping connection with and readily separable from the latter, a burner supporting member carried dependingly by said burner and having its lower free end extended through an aperture in and supported on said bottom wall at a point laterally spaced from said supply connections, and removable grid means carried by said casing over said burner and permitting access to said burner and supporting member.
- 20 19. A stove casing having generally vertically disposed front, back and end plates connected at their meeting edges, a bottom member supported by said plates, grid supporting members along said front and back plates, grids carried by said members, and corner housing and covering members enclosing the meeting edges of said plates and clamping said casing therebetween.
- 25 20. In a stove having a casing, a tubular casing corner housing member having longitudinal slots therein at right angles to one another to receive the ends of adjacent sides of said casing, and a grid support, each of said slots being provided at its upper end with an enlarged slot to receive the end of said grid support and extending laterally toward the other enlarged slot.
- 30 21. A grid unit comprising an elongated grid member and a co-operating grid member pivotally connected thereto intermediate its ends, said co-operating member having its ends parallel to the ends of said first mentioned member and having an intermediate grid portion pivoted on the latter member.
- 35 22. In a stove having a casing, a tubular casing corner housing member having peripherally spaced apart longitudinal slots therein and open at one end of said member to receive the ends of adjacent sides of said casing, and a grid support, said housing member also having a longitudinal slot disposed adjacent the open end of each of said first mentioned slots and in communication therewith along the entire length of the last mentioned slot to receive an end of said grid support.
- 40 23. In a stove having a casing, a tubular casing corner housing member having peripherally spaced apart longitudinal slots therein to receive the ends of adjacent sides of said casing, and a grid support, said housing member also having a longitudinal slot disposed at one end of each of the first mentioned slots to receive an end of said grid support and extending peripherally to wards each other between said first mentioned slots.
- 45 24. In a stove, a casing having a bottom, a grid forming the top of said casing, a burner within said casing between said bottom and said grid, and a support for said burner at substantially the axial center thereof including means depending from said burner having a portion at its lower free end extended through a passage in and supported on said bottom.
- 50 25. A stove having a casing, grid supporting members on opposite sides of said casing, a plurality of grid units removably supported by said members, each of said units comprising a straight rod, and a cooperating rod having an arcuate portion intermediate its ends, said straight rod being connected to said cooperating rod at the arcuate portion thereof.
- 55 26. A stove casing comprising front, back and end plates rigidly connected at their corners and having frame members disposed along their upper edges and terminating short of the corners, and corner housing and covering members enclosing the corners, supporting the respective plates thereat and engaging the ends of said members to support the same.
- 60 27. In a stove, a casing, grid supporting means, a plurality of grid units, each grid unit being separately removably supported by said supporting means and each unit comprising a bar having end portions loosely received on said supporting means and an arcuate portion intermediate its ends, and means to retain said bar thus loosely on said supporting means with its arcuate portion substantially disposed in a horizontal plane.
- 65 28. In a stove, a casing having opposing side members, grid-carrying members rigidly secured upon the inner surfaces of said side members, and a plurality of grid rods extending from one carrying member to the other, said plurality of grid rods being arranged in groups of two or more, the rods of one group being secured to said carrying members and the rods of another group removably resting upon said carrying members.
- 70 29. In a stove, a casing having opposing side members, grid-carrying members rigidly secured upon the inner surface of said side members, and a plurality of grid rods extending from one carrying member to the other, said plurality of grid rods being arranged in groups of two or more, the rods of one group being secured to said carrying members and the rods of another group being secured together intermediate their ends and removably resting upon said carrying members.
- 75 30. In a stove, a casing having opposing side members, grid-carrying members rigidly secured upon the inner surface of said side members, and a plurality of grid rods extending from one carrying member to the other, said plurality of grid rods being arranged in groups of two or more, the rods of one group being secured to said carrying members and the rods of another group removably resting upon said carrying members, one of the rods of the first-mentioned group being adapted to draw said carrying members together.
- 80 31. In a stove, a casing having opposing side members, grid-carrying members rigidly secured upon the inner surfaces of said side members, said carrying members having alternate groups of notches in their upper edges and openings in their sides, and a plurality of grid rods extending from one carrying member to the other, said plurality of grid rods being arranged in groups of two or more, the rods of one group being secured to each carrying member within the openings in

the side thereof, and the rods of another group removably and freely resting in the notches in the upper edge of each carrying member.

32. In a stove, a casing having opposing side members, grid-carrying members rigidly secured upon the inner surfaces of said side members, said carrying members having alternate groups of notches in their upper edges and openings in their sides, and a plurality of grid rods extending from 10 one carrying member to the other, said plurality

of grid rods being arranged in groups of two or more, the rods of one group being secured to each carrying member within the openings in the side thereof, and the rods of another group removably and freely resting in the notches in the upper edge of each carrying member, the rods of said last-named group being secured together in pairs to prevent twisting thereof in the notches in which they rest.
